ATTORNEY

UNITED STATES PATENT OFFICE.

ROBERT G. ODELL, OF PEEKSKILL, NEW YORK.

PAPER-HANGER'S COMBINATION-TOOL.

SPECIFICATION forming part of Letters Patent No. 651,380, dated June 12, 1900.

Application filed January 2, 1900. Serial No. 70. (No model.)

To all whom it may concern:

Be it known that I, ROBERT G. ODELL, a citizen of the United States, and a resident of Peekskill, in the county of Westchester and State of New York, have invented a certain new and useful Paper-Hanger's Combination-Tool, of which the following is a specification.

My invention relates to tools used by paper-hangers, and has for its object the convenience and saving of time of paper-hangers by combining in one several of the devices they most employ. This object is attained by the means set forth in the specification and the drawings accompanying it.

15 An explanation will first be made of the several views of the drawings, in which like letters and numbers refer to like parts in the several views.

Figure I represents a pair of shears having a paper-trimmer and seam-roller attached to the handles thereof. Fig. II indicates how the tool is used on a straight edge as a paper-trimmer. Fig. III is an edge view of the paper-trimmer and its shield. Fig. IV is a side view of the seam-roller, and Fig. V is a cross-sectional view thereof. Fig. VI is an end view of the paper-trimmer shield. Fig. VII is a cross-sectional view of the shears-handle at line b, Fig. I.

30 A paper-hanger's outfit embraces a pair of shears, a base-trimmer, a trimmer to use on a straight edge, a seam-roller, and a side-seam roller. These, with such other small tools as he needs, he carries in a pouch in his apron, and it is often at great inconvenience that he exchanges one tool for another. Some of the most used of these tools I have combined upon a pair of shears as a handle without sacrificing any of the advantages belonging 35 to them separately.

As shown in Fig. I, the seam-rollers are applied to the thumb-handle 1 of the shears and the trimmers to the finger-handle 2. An arm 9 is extended from the handle 1. (See Figs.

45 I, IV, and V.) It is a plain extension tapped at the end for a stud 11. The seam-roller 10 may have a straight face, as in Fig. I, or it

may be oval, as in Fig. V. Both shapes are used and both would accompany the shears, they being made interchangeable, so that the 50 possessor could use either at will or retain permanently whichever he preferred in his practice.

The handle 2 of the shears is provided with an extension 4, Fig. I, in a form to support 55 a rotary cutter 6, herein called a "trimmer." As this support is made broad enough to serve as a shield for the trimmer, it is preferably made thin, a boss 15 being added on the outside to give thickness for a screw-thread. A 60 screw 5, entering the boss, holds the trimmer in place. Opposite the boss 15 is a lower one 13, Figs. II and VI, designed to give a clearance 14, Fig. III, behind the trimmer, so that it will not soon become clogged with bits of 65 paper and paste. As a further shield to the trimmer flange 7 is made to partly encircle it.

As thus far described the trimmer is complete as a "base-trimmer." To adapt it for straight-edge trimming, guide-flanges 3 and 70 8 are added to the handle 2; but little change is made in the original shape of the handle. The outer surface is made straight, as at 8 in Fig. VII, and the flange 3 is added. This conformation is extended to and upon the 75 trimmer extension close to the cutter, as in Fig. I. Fig. III shows that the face of the flange 3 and the face of the trimmer lie in the same plane. The manner of using the flange and trimmer on a straight edge is shown in 80 Fig. 2, the straight edge a being between the observer and the trimmer. Thus the tool shown in Fig. I embraces a pair of shears, a straight-edge trimmer, a base-trimmer, a seam-roller, and a side-arm seam-roller, with 85 no alteration of the handles of the shears that will affect its ordinary handling as a pair of shears, while it brings in play all the other devices as handily as if they were each on distinct handles. The construction adds very 90 little to the weight of the shears.

Having described my invention, what I claim, and desire to secure by Letters Patent, is—

1. A combination - tool for paper-hangers comprising a hand-shears having a trimmer attached to one of the handles of the shears, and protected by a partially-surrounding shield, 5 substantially as herein set forth.
2. In a combination-tool for paper-hangers, substantially as shown, guide-flanges on the edge of one of the handles of the shears and a paper-trimmer supported on the end of the

10
said handle in the same plane with one of the guide-flanges, substantially as herein shown.

Signed at Peekskill, in the county of West-
chester and State of New York, this 9th day
of December, A. D. 1899.

ROBERT G. ODELL.
